CURTAIN, DRAPERY AND BLIND MOUNTING PLATE

Wayne W. Wallace, Youngstown, Ohio

Application February 7, 1955, Serial No. 486,503

3 Claims. (Cl. 248—263)

This invention relates to a mounting plate for draperies, curtains and blinds.

The principal object of the invention is the provision of a mounting plate to which brackets for supporting curtains, draperies and blinds may be attached with various degrees of adjustment and in various positions.

A further object of the invention is the provision of a universal mounting plate for drapery and blind fixtures.

A still further object of the invention is the provision of a mounting plate for drapery, curtain and blind fixtures incorporating means for locking the various fixtures thereto in suitably adjusted relation.

A still further object of the invention is the provision of a mounting plate which may be secured to a window casing or a wall surface adjacent a window opening which will receive many and various forms of drapery, curtain, roller shade and Venetian blind mounting brackets to the end that draperies, curtains, roller shades or Venetian blinds may be desirably and safely supported thereby.

A still further object of the invention is the provision of a mounting plate which may be secured on a wall surface adjacent a window opening either by direct attachment to the wall surface or by indirect attachment to a window casing through a fixture secured in the mounting plate.

The mounting plate and the fixtures engageable therewith disclosed herein comprises an improved means for securing curtain and drapery rods as well as roller blinds to a window casing or to a wall surface adjacent a window.

Those skilled in the art will recognize that it has been common practice to mount one or more fixtures on a window casing near the upper corners thereof or to the wall surface adjacent the same, which fixtures are used to support various curtain and drapery rods as well as roller and Venetian blinds. Practically all manufacturers heretofore have utilized different forms of fixture and specifically the brackets which are secured to the window casing or wall surface and to which the actual curtain or drapery rods, roller blinds or Venetian blinds are then affixed.

In rental properties the problem of continually changing such fixtures to meet the requirements of the various tenants is expensive as well as damaging to the window casing and/or wall surface adjacent the same.

The mounting plate disclosed herein eliminates the several difficulties in that any and all forms of curtains, drapes, roller or Venetian blinds may be quickly and inexpensively secured thereto with the plate remaining in position for subsequent use by other tenants.

With the foregoing and other objects in view which will appear as the description proceeds, the invention resides in the combination and arrangement of parts and in the details of construction hereinafter described and claimed, it being the intention to cover all changes and modifications of the example of the invention herein chosen for purposes of the disclosure, which do not constitute departures from the spirit and scope of the invention.

2

The invention is illustrated in the accompanying drawing, wherein:

Figure 1 is a plan view of the mounting plate.

Figure 2 is a top plan view of the mounting plate.

5 Figure 3 is an enlarged detail of the mounting plate and a fixture positioned therein with parts broken away.

Figure 4 is an enlarged cross section taken on the line 4—4 of Figure 3.

10 Figure 5 is a perspective view of an alternate form of fixture.

Figure 6 is a perspective view of the mounting plate positioned on a wall surface adjacent a window opening.

By referring to the drawings and Figures 1, 2, 3 and 4 in particular it will be seen that a plate 10, preferably rectangular in shape, is provided with flanged edges 11, three of which are apertured at spaced intervals therealong by a plurality of slot-like openings 12—12. Each of the slot-like openings 12—12 is located in the flanged edges 11 of the plate 10 and are preferably of a configuration precluding the possibility of inserting a flat fixture therein.

The slot-like openings 12—12 are positioned so that appropriately shaped fixtures, such as shown in Figure 3 of the drawings in Figure 3 and indicated by the numeral 13, may be slidably engaged in the slot-like openings 12 with the innermost end portion extending inwardly adjacent the back side of the plate 10 and into engagement with a locking cam 14 which is actuated by a screw-like head 15 located on the front surface of the plate 10.

25 The plurality of slot-like openings 12 are so arranged in the flanged edge 11 of the plate 10 that a fixture positioned in any one of the openings will engage one of a pair of cams 14 rotatably secured to the plate by the screw-like head 15.

30 The plate 10 is also embossed as at 16—16 to form members engageable with the opposite sides of the slide portion of the fixtures 13 so that the clamping action of the cams 14 will be suitably opposed thereby and the fixtures secured in desired position to the mounting plate 10.

35 The plate 10 is also provided with a plurality of orifices 17 through which mounting screws 18 may be positioned in mounting the plate on a window casing or wall surface. Alternately, an L-shaped bracket 19 may be inserted in one of the slots 12 and clamped to the mounting plate by the adjacent cam 14 with the other end of the L-shaped bracket 19 being affixed to a window casing 20 by fasteners 21. Such an arrangement may be seen by referring to Figure 6 of the drawings, and by referring thereto it will be observed that a pair of drape and curtain supporting fixtures 22 and 23, respectively, are secured in the slot-like opening 12 in the plate 10 in different degrees of adjustment with respect thereto

40 so that curtain rods may be attached to the lower inner fixture 23 and drapery rods attached to the upper outer fixture 22.

45 It will be obvious to those skilled in the art that if the window casing 20 extends around onto the face of the wall adjacent the window, the L-shaped bracket 19 may be dispensed with and the mounting screws 18 relied upon to secure the plate 10 in desirable position.

50 By referring again to Figure 3 of the drawings an enlarged detail of the embossing 16 may be seen together with a detail of one of the cams 14 and its actuating screw-like head 15.

55 In Figure 4 of the drawings a section of the plate 10 is taken through one of the cams 14 and it will be observed that the screw-like head 15 has a threaded shank 24 thereon on which the cam 14 is threaded with the threaded shank 24 being peened into the cam 14 as at

25 to render the same fixed with respect thereto and enable the cam 14 to be rotated by the screw-like head 15.

It will be obvious to those skilled in the art that various sizes of mounting plates may be made within the scope of this disclosure and that more than the disclosed pair of cams 14 may be employed if desired.

In Figure 5 of the drawings a perspective view of a different fixture may be seen, which fixture may be mounted to the mounting plate 10 and secured thereto. The fixture comprises an appropriately shaped slide section 26 of a cross sectional shape registerable with one of the slot-like openings 12 and having an end portion 27 doubled back over the face thereof, the end portion 27 having an outturned portion 27A which in turn is provided with a diagonally extending slot 28 in which a roller blind may be conveniently positioned.

It will be observed that the slide section 26 may be positioned in any of the slot-like openings 12 of the mounting plates and that in addition to the adjustment thereby provided as to location, the fixture may be located in partially or completely extended relation to the plate or in telescopic relation thereto thus enabling the particular length of the roller blind employed to be matched and accommodated.

Those skilled in the art will observe that while the drape and curtain supporting fixtures 22 and 23 disclosed herein are of the type terminating in forwardly projecting bifurcated hooked ends, the other types known in the art may be substituted to the end that any and all types of drapery and curtain rods may be secured to the fixtures which are themselves adjustably secured in the mounting plate 10.

It will thus be seen that the mounting plate disclosed herein meets the several objects of the invention.

Having thus described my invention, what I claim is:

1. The combination of a mounting plate and a plurality of blind, drape and curtain supporting fixtures for selective engagement therewith, said plate comprising a rectangular body member having the edge portion thereof flanged at a substantial angle with respect thereto, said edge portion having a plurality of spaced longitudinally extending slot-like openings therein for receiving said fixtures, said fixtures comprising elongated sections registerable in said slot-like openings having outturned edge portions adapted to receive and retain said drapes,

40
45

curtains and blinds, cams rotatably secured to said plate inwardly from the edge portion and out of transverse alignment with said slot-like openings, portions of said cams extending through said plate and including screw heads on the face of said plate whereby the cams may be rotated when said plate is mounted on a supporting surface.

2. A mounting plate for attachment to a supporting surface and incorporating means for receiving and retaining drapery, curtain and blind mounting fixtures, said fixtures having longitudinally extending portions, flanges on the edges of said mounting plate having spaced slot-like openings therein for receiving the elongated portions of said fixtures, guide means on the back of said plate for engaging said elongated portions of said fixtures positioned through said slot-like openings and substantially square cam discs on screw-headed shanks positioned rotatably through openings in said plate in oppositely disposed relation to said guide means for engaging and securing said fixtures and fasteners for securing said plate to a supporting surface.

3. A mounting plate for attachment to a supporting surface and incorporating means for receiving and retaining drapery, curtain and blind mounting fixtures, said fixtures having longitudinally extending portions, flanges on the edges of said mounting plate having spaced slot-like openings therein for receiving the elongated portions of said fixtures, guide means on the back of said plate for engaging said elongated portions of said fixtures positioned through said slot-like openings and substantially square cam discs on screw-headed shanks positioned rotatably through openings in said plate and located on said plate at points adjacent lines interconnecting oppositely disposed pairs of said slot-like openings for engaging and securing said fixtures, and fasteners for securing said plate to a supporting surface.
